CLAIM

The ornamental design for an electronic torch, as shown and described.

DESCRIPTION

FIG. 1 is a isometric view of an electronic torch; FIG. 2 is a right side view of the electronic torch of FIG. 1; FIG. 3 is a left side view of the electronic torch of FIG. 1; FIG. 4 is a front view of the electronic torch of FIG. 1; FIG. 5 is a back view of the electronic torch of FIG. 1; FIG. 6 is a top view of the electronic torch of FIG. 1; and, FIG. 7 is a bottom view of the electronic torch of FIG. 1. The broken-line disclosure represents portions of the electronic torch which form no part of the claimed design.
